UNITED STATES PATENT OFFICE.

JAMES B. BRISTOW, OF MONROE CITY, MISSOURI.

LIFTING-JACK.

1,317,857.

Specification of Letters Patent.

Patented Oct. 7, 1919.

Application filed September 19, 1917. Serial No. 192,137.

To all whom it may concern:

Be it known that I, JAMES B. BRISTOW, a citizen of the United States, residing at Monroe City, in the county of Monroe, State 5 of Missouri, have invented certain new and useful Improvements in Lifting-Jacks; and I do hereby declare the following to be a full, clear, and exact description of the invention, such as will enable others skilled in 10 the art to which it appertains to make and use the same.

This invention relates to lifting jacks.

The object of the invention is to provide an improved form of lifting jack for use in 15 jacking up vehicles, particularly in garages where motor vehicles must be lifted for repair in great numbers. In storage and repair garages, motor vehicles of all makes are indiscriminately brought together, and 20 repair men and cleaners must place jacks under axles and other parts which seldom stand in the same height. Those jacks which are now in the market and known to me must be manually adjusted to the particular 25 vehicle or part to be lifted before the jacking action can be begun, and it is the intention of this invention to provide a jack which automatically accommodates itself to 30 the height of the part to be lifted and is then automatically locked at the proper height so that the jacking action can be begun.

More particularly, it is the object of this 35 invention to provide an automatically adjustable jack which depends upon the height of an oil cushion for its adjustment to the height of the part to be jacked up, and upon the pressure exerted by the object to be lifted for the locking of the jacking element at the proper height.

40 With the above objects in view, and such others relating to the details of construction as may hereinafter appear, my invention will now be fully set forth and described, reference being had to the accompanying 45 drawings.

In the drawings:—

Figure 1 is a side elevation,

Fig. 2 is a longitudinal section,

Fig. 3 is a view showing the device adjust- 50 ed, prior to the lifting action,

Fig. 4 is a longitudinal section showing the device supporting an axle,

Fig. 5 is a section on line 5—5 of Fig. 2, and

Fig. 6 is a section on line 6—6 of Fig. 2.

Referring more particularly to the drawings, 1 represents a preferably cylindrical oil chamber which is supported upon a pair of jack wheels 2. Operative within the chamber or cylinder 1 is a piston 3 which is held in place by means of a bushing plug 4 and has its head suitably packed or capped as at 5, to prevent the passage of oil past the head. The exposed end of the piston 3 is provided with a suitable saddle 6 for the engagement of an axle or other part to be lifted.

At its lower end, the cylinder 1 extends to one side in a reservoir 7 which is divided from the cylinder by means of a partition 8 centrally provided with a valve casing 9. The casing 9 includes a seat 10 which opens toward the cylinder 1, and a spider or stop 11 which limits the unseated movement of a valve 12. The valve 12, which is thus confined between the spider 11 and the valve seat 10 has a stem 13 which projects through the seat, and behind the latter is surrounded by a coil spring 14 which bears between the valve head and a grid 15 formed across the rear of the valve chamber, so that the valve is normally unseated thereby. The expansive ability of the spring 14 is such that it will hold the valve 12 off of its seat under a certain predetermined pressure upon the piston 3, but will close when that pressure is exceeded.

The chamber or reservoir 7 is capped by a closure fitting 16 which forms the head of a hollow handle 17. The handle 17 extends from the head 16 in a downwardly arched length, so that a foot portion 18 rests upon the ground surface when the jack stands in lifting position. As above stated, the handle 17 is hollow, and furthermore, is provided with an air connection 19, by means of which air under pressure may be blown into the handle. When the parts are assembled, the handle 17 forms a continuation of the reservoir 7, and when air is blown into the handle the pressure assists the spring 14 in holding the valve 12 off of its seat. And furthermore, insures the unseating of the valve as soon as a supporting part is removed from the piston. The air which is blown into the handle 17 need not be of any greater pressure than can be blown in by the application of the mouth to the air inlet 19, a one pound pressure being usually all that is needed.

In assembling the above described device, the bushing 4 is removed, together with the piston, and the chamber 1 and reservoir 7 fill with oil to the point where room is just 5 provided for the piston 3 and the return of the bushing 4. Then, the air inlet 19 is opened and air forced therein under sufficient pressure to insure the unseating of the valve 12 when the jack is not in use. Then, 10 in order to elevate a weight, the jack is tipped forwardly until the saddle 6 can be brought below the axle or another part to be lifted. Then, the handle 17 is carried gradually and steadily downward until the 15 piston 3 has been carried a sufficient distance into the cylinder 1, by its bearing upon the axle. When the proper point of adjustment has been reached, the handle 17 is given a sudden downward jerk. This 20 causes a quick increase in the pressure upon the saddle 6, and consequently causes the piston 3 to react upon the oil cushion within the cylinder 1 to close the valve 12 against the spring 14. Continued downward movement of the handle 17 will then 25 cause the change in the position of the jack from that shown in Fig. 3 to the operative position of Fig. 4, the continuous application of the weight of the body lifted to the 30 piston 3 holding the valve 12 upon its seat.

As soon as the jack is removed from below the lifting body and the piston is relieved of its weight, the air pressure in the upper end of the handle 17, together with 35 the action of the spring 14 will open the valve 12, thereby placing the jack in readiness for adjustment to another vehicle. If it is desired to maintain the jack at a constant position of adjustment, as when it is 40 used in lifting a number of cars of the same

type, it is placed in its lifting position below the first car. Then, the air inlet 19 is opened to permit the escape of the air. Then, when the jack is removed from under the first car, the valve 12 will not open, and consequently the piston 3 will remain in the 45 position of adjustment, and can be thus maintained until the air pressure is restored, in the handle 17.

From the foregoing description it will be 50 apparent that the improved form of jack which I have evolved will save a great deal of labor and time in garages and shops where automobiles and other weights must be frequently lifted, since by the same action 55 which lifts the weight, the jack can be adjusted to the height of the weight to be elevated, the user being thereby relieved of the necessity of stooping below the car or to the jack body for a preliminary adjustment 60 for operating the lifting handle.

What I claim as my invention is:—

A lifting jack comprising a cylinder, a wheeled support for one end of the cylinder, a piston slideable in the cylinder, a stem for 65 said piston projecting from the other end of the cylinder, a reservoir in communication with the cylinder and a valve for controlling the flow of fluid between said cylinder and reservoir, said valve being normally 70 open and adapted to close upon the occurrence of predetermined pressure in the cylinder, and means for propelling and rocking the cylinder.

In testimony whereof I affix my signature 75 in the presence of two witnesses.

JAMES B. BRISTOW.
